SLUG CASTING MACHINE

Frank C. Frolander, Elizabeth, N. J., assignor to
 Mergenthaler Linotype Company, a corpora-
 tion of New York

Application April 1, 1935, Serial No. 14,047

71 Claims. (Cl. 199—50)

This invention relates to slug casting machines, such as Linotype machines of the general organization represented in U. S. Letters Patent to O. Mergenthaler, No. 436,532, wherein circulating 5 matrices and expandable spacebands are composed in line by the manipulation of a keyboard, the composed line transferred to a slotted mold for the casting of a type bar or slug, and the matrices and spacebands thereafter separated 10 and returned by a distributing mechanism to the magazines from which they started.

More particularly, it relates to machines equipped to handle not only lines of full length as ordinarily, but in addition lines of less than 15 full length (regardless of their actual length). Under certain conditions, the two line clamping jaws are movable equi-distantly toward each other until arrested by contact with the opposite ends of the composed line for "centering"; whereas under other conditions, one jaw or the 20 other is movable independently into contact with the line, for quadding at the right or at the left, as the case may be. Heretofore, the operation of the machine for centering, quadding left or quadding right, has been determined by conditioning 25 mechanism settable manually in one of three positions depending upon the condition desired, or to a fourth position if the machine is to operate normally or without quadding or centering.

30 When the latter condition exists, the machine is free to function in the usual way, the right hand jaw being left normally stationary and the left hand jaw being adjustable by the customary devices.

35 According to the instant invention, it is proposed to operate the conditioning mechanism automatically during a machine cycle of operation, and to control the operation of such mechanism by keys arranged adjacent the keyboard 40 within convenient reach of the operator or by a perforated tape through mechanism similar to that used in the so-called Teletypesetter machine.

More specifically, the conditioning of the two 45 line clamping jaws (which are operated through two distinct trains of connections from a vertically movable rod actuated directly from the main shaft of the machine) is effected by a grooved collar mounted for rotation only at the upper end of the vertically movable rod, the collar 50 being rotatable from neutral position through a quarter turn in one direction to engage a pin associated with one train of connections (e. g., the one for operating the right hand jaw) to condition the machine for quadding at the right, and 55 also rotatable from neutral position through a

quarter turn in the opposite direction to engage pins associated with both trains of connections to condition the machine for "centering".

When the collar is in its neutral position, ordinarily it stands clear of both pins so that neither 5 train of connections is rendered operative, the machine under such circumstances being free to operate in the usual way.

In the present instance, however, the neutral position of the collar is utilized for left hand quadding, the pin associated with the train of connections for operating the left hand jaw being made movable to engage the collar and thus bring the left hand jaw under the control of the vertically movable rod. 10

The rotation of the grooved collar is brought about by a pair of toothed rack bars slidably mounted on the vise frame and connected to the grooved collar through suitable gearing, the arrangement being such that when one of the rack 20 bars is moved downwardly the grooved collar is rotated in one direction to effect the conditioning of the mechanism for quadding right, whereas when the other rack bar is moved downwardly, said collar is rotated in the opposite direction to 25 effect the conditioning of the mechanism for "centering". The return movement of the rack bars restores the grooved collar to neutral position. 15

The movement of the pin to condition the machine for quadding left is brought about by a U-shaped lever, pivotally secured in the vise frame, and swingable in a horizontal plane in one direction to effect engagement of the pin with the collar and in the opposite direction to 30 effect disengagement of the pin therefrom. 35

The setting of the rack bars and of the U-shaped lever as well as their restoration to normal position are brought about by the line transporter or first elevator, which is equipped with 40 actuating devices (one for each rack bar and for the U-shaped lever) selectively rendered active by mechanism controlled by the operator at the keyboard or by the tape operated mechanism 45 referred to above.

These and other features of the invention will be fully set forth in the detailed description to follow.

Referring to the drawings:

Fig. 1 is a front elevation of a portion of a 50 Linotype machine equipped with the present improvements;

Fig. 24 is a skeleton perspective view of the teletypesetter mechanism and electrical connections for automatically operating the "quadding" and "centering" controls;

Fig. 25 is a diagrammatic view, showing a set of code bar links used in the teletypesetter mechanism in four different positions of adjustment, the bars being inverted to show the combination notches therein; and

Fig. 26 is a detail plan view of a portion of the tape employed in the teletypesetter mechanism, showing the "centering" symbol in advance of the character and space symbols of a composed line;

The matrices X and the expandible spacebands Y (see Figs. 1, 8, and 9) are composed in line in the assembler A under the restraining influence of a line resistant which can be set for lines of different length, all in the usual way. After the line has been composed, the assembler is raised to position the line between the fingers of the line delivery carriage B, which thereupon moves to the left (and in doing so inaugurates the operation of the machine) and transfers the composed line through an intermediate channel B¹ into the vertically movable transporter or first elevator C slidably mounted in the vise frame D. Upon receiving the line, the first elevator immediately descends to position it between the left hand jaw E and the right hand jaw F and in front of the slotted mold G, which latter then advances from the rear and into contact with the line and the two clamping jaws for the slug casting operation, the line, prior to casting, being alined and justified in the usual way when the machine is being operated under the usual conditions. After the slug has been cast, the mold is carried from its horizontal casting position (as shown in Fig. 1) to a vertical ejecting position by a three-quarter rotation of the mold disc G¹, the first elevator in the meantime being raised to deliver the composed line to the matrix and spaceband distributing devices and finally coming to rest in its original or line receiving position.

The line clamping jaws E and F are operable automatically to cooperate with lines of less than full length so as to cast slugs with blank spaces at either end, as for "quadding", or at both ends as for "centering". For this purpose, the two jaws E and F are movable toward and from each other by a periodically operated part in the form of a vertically movable rod H which may be connected at its upper end to the respective jaws through the medium of two similar or oppositely disposed bell crank levers E² and F² pivoted at E³ and F³ to the vise frame D, the longer arms of said levers being connected by short links E⁴ and F⁴ to jaw supports E¹ and F¹ respectively, and the shorter arms of said levers being arranged for connection to the rod H. According to this arrangement, when the rod H is moved downwardly from its uppermost position (which is the normal position of rest), it will move the two jaws E, F equidistantly toward each other (assuming both to be connected to the rod) until they contact with the opposite ends of a composed line which has previously been positioned between them, and when the rod is moved upwardly to its position of rest, it will in like manner move the jaws equi-distantly away from each other to return them to their original positions of maximum separation. Since the composed lines positioned between the jaws may vary in length, the actual extent of movement of the rod H will of course vary accordingly.

In providing for the connection and disconnection of the rod H with and from the jaws E and F, the rod (see Fig. 10) is provided at its upper end with a grooved collar N formed for engagement with diametrically opposed pins N¹ and N² protruding inwardly from the extremities of the horizontal arms of the actuating levers E² and F² for the jaws E and F, respectively. While the particular construction and operation of the collar N forms part of the present invention, suffice it to say at the moment there are four conditions provided for; the first or normal condition wherein neither of the jaws E and F is connected with the rod H and thus

will remain in their fully separated positions to accommodate lines of normal or full length; a second condition wherein the right hand jaw F is connected to the rod H for quadding right; 5 a third condition wherein the left hand jaw E is connected to the rod H for quadding left, and a fourth condition wherein both jaws are connected to the rod H for centering.

The rod H is slidable in suitable bearings H² 10 and H³ of the fixed vise frame D, being provided about midway of its length with a collar H¹ carrying an adjusting screw (not shown) which banks against the underside of the bearing H² when the rod is in its uppermost or normal position of rest. The extent to which the rod H 15 will descend during a quadding or centering operation will depend solely upon the length of the line between the line clamping jaws and, when the rod in its descent is arrested by the 20 contact of the line clamping jaws with the ends of the line, it is locked in its arrested position.

In order to lock the rod H in its downwardly moved position, there is provided a toggle member J (see Fig. 4) enclosed within a box or housing D¹ which carries the bearing H³ before alluded to. This toggle member J operates a clamp or grip element J¹ arranged to contact with a sleeve T carried by the rod H. For the purpose of the present description it is unnecessary 30 to go into the details of construction and operation of the actuating mechanisms for the rod H and toggle lock J, except to say that both are controlled and actuated in proper time sequence from a cam mounted on the main drive shaft of the machine.

Were the rod H and its sleeve T actually joined together as one, it is plain that there could be no spread of the composed line after the sleeve is locked in position by the toggle member J and, in such circumstances, the jaws would be locked directly in their line contacting positions which actually happens when the lines are composed without spacebands. However, the arrangement is such that the jaws may be moved 45 outwardly from their line contacting positions to a limited extent after the locking of the sleeve T in order that a composed line may be spread to a corresponding extent under the expanding influence of the spacebands Y, provision being 50 made usually for allowing the line to spread up to three ems in extent. This is accomplished by providing for a relative movement between the rod H and the sleeve T after the latter has been locked by the toggle member J in the downwardly moved or line clamping position.

Referring particularly to Fig. 4, it will be noted that at its lower end the rod H is provided with a fixed collar T¹ which contains an expansion spring T² encircling the rod H and pressing upwardly on the lower end of the sleeve T. This lifting tendency of the spring T², however, in the downwardly moved position of the rod H is resisted and overcome by one or another of a pair of rotary cams V or V¹ carried by a sleeve 65 V² rotatably mounted on a stud fixed to a bracket T³ carried at the upper end of the sleeve T and arranged to engage a roller h carried by a collar H¹ pinned to the rod H and, when either of the cams in its operative position is set with 70 its high point in contact with the roller h, it will by reacting thereagainst and over the opposition of the spring T², hold the sleeve T in contact with the fixed collar T¹ at the lower end of the rod. Under such setting of the cams as 75 will now be evident, there can be no relative

movement between the rod H and the sleeve T and the two parts function as if they were rigidly united, which is the condition that would exist when casting from lines without spacebands. On the other hand, when either of the cams is set, 5 say to bring its lowest point in contact with the roller h, then the sleeve T in the downwardly moved position of the rod H will be raised by the spring T² out of engagement with the collar T¹, and the clearance thus provided will determine the amount of relative movement which can take place between the rod and sleeve after the locking of the latter by the toggle member J in the manner before described. This is a condition that should exist when it is desired 15 to permit the maximum spread of a composed line during justification, which ordinarily is three ems. When it is desired to provide for a less spread of a composed line, the cam V or V¹ in use is set in an intermediate position, 20 that is to say in a position intermediate its lowest and highest points.

The upward movement of the rod H to spread the jaws for expansion of the line is effected by mechanism not herein shown, but which is operated by a cam arranged on the main drive shaft of the machine and acting through suitable mechanism to actuate the rod H. The cam just referred to comes into operation after the sleeve T has been locked in its downward position by 30 the toggle member J and acts to move the rod H upwardly with reference to the sleeve T until the rod collar T¹ banks against the lower end of the sleeve, the extent of such relative movement of the rod being, as previously stated, determined 35 by the setting of the cams V or V¹, whichever happens to be in operative position. It is this upward limited movement of the rod H which moves the line clamping jaws outwardly from their line contacting position and thus determines the final 40 quadding or centering position of the jaws when a composed line is to be spread or justified by the expansion of the contained spacebands.

If it is borne in mind, now, that the extent of line spread during justification should be uniform 45 irrespective of whether the line is to be presented to the mold at the "centering" or at either of the quadding positions, the reason for the two cams V and V¹ is at once apparent. If but one cam were used and such cam were set 50 to produce, say a one em spread of the jaws if the rod H were connected to but one jaw, as in quadding right or left, the same setting of the cam would result in twice such amount of spread if the rod were connected to both of the line 55 clamping jaws, as in centering, since any movement of the rod H is reflected in a corresponding movement of any jaw which happens to be connected to the rod H at the time.

In order therefore to insure the same spread 60 of the jaws during both centering and quadding for a line of a given measure, the two cams V and V¹ have been provided, mounted for rotation about the same axis but differing in eccentricity, the one of greater eccentricity being brought into 65 register with the roller h for centering, and the one of lesser eccentricity into register with said roller during quadding, either left or right. The adjustment of the cams in one position or another is effected automatically during the conditioning of the machine for the performance of the centering and quadding functions and will be described hereinafter.

It should be noted that if the jaws E and F are set for a maximum spread of say three ems 75

during justification for a line of full measure, it will not be desirable to have this same degree of spread for a line of say half measure. Under normal conditions, the average number of spacebands per unit length of line will be the same regardless of its length so that by decreasing the extent of spread of the jaws in proportion to the extent of inward movement of the jaws during quadding or centering, the proper amount of spread of the jaws for a line of any given measure will result. This is provided for in the present machine by rotating the cams V and V¹ automatically to some intermediate position depending upon the extent of downward movement of the rod H. Referring to Figs. 2 and 4, it will be seen that the cam sleeve V² at its left end is connected through a pin V³ with a crank arm V⁴ formed at its free end with an elongated slot V⁵ through which a stud V⁶ formed at the outer end of another crank arm V⁷ extends. Throughout the operation of the machine, the stud V⁶ remains stationary and as the sleeve T descends with the rod H during a quadding or centering operation, the crank arm V⁴ will turn about the stud V⁶ as a pivot, and consequently turn the cams V and V¹ to some intermediate position of adjustment depending upon the extent of downward movement of the rod H. The adjusted position of the cams V or V¹, whichever happens to be active, will thus determine the extent of jaw spread in the manner previously described.

Then again it may be desirable to provide initially for the casting of lines of less than normal length by adjusting the left hand jaw E to the right with respect to its movable support. In the casting of such shorter lines, the maximum spread of the line clamping jaws to accommodate for the expansion of the spaceband should bear the same ratio to the maximum spread of the jaws when a line of full measure is cast as the length of the respective lines bear to each other. In the present machine, this condition is provided for by initially setting the cams V and V¹ automatically to some intermediate position depending upon the adjustment of the left hand jaw. Thus when the arm V⁷, which is pivoted at its rear end to the vise frame, is turned in a clockwise direction (see Figs. 2 and 4), it will through the pin and slot connection with the arm V⁴, turn the latter to bring an intermediate portion of the cams V or V¹ (whichever is active) opposite the roller h. With this initial setting of the cams V and V¹, the center and quadding devices will operate the same as before, further reducing the extent of line spread for lines shorter than the maximum length capable of being accommodated between the right hand jaw and the left hand jaw in the adjusted position of the latter. To effect the adjustment just referred to, the arm V⁷ at its center is connected by a line V⁸ through mechanism V¹³ (see Fig. 1) with the left hand line clamping jaw E, the arrangement being such that, as said jaw is moved to different positions of adjustment, such movement will automatically set the cams V and V¹ to vary the extent of jaw spread in the manner previously described. It is unnecessary to describe the mechanism V¹³ in detail, as it is not concerned with the present invention.

The mechanism so far described, except as hereinafter pointed out, is the same as set forth in the patents to Frolander No. 1,971,400 and Morrison et al. No. 1,971,424, to which reference may be had for any further details. According to the present invention, as before stated, the col-

lar N, which effects the connection of the line clamping jaws E, F to the vertically movable rod H, is set automatically for quadding left or right or for centering during a machine cycle of operation by conditioning mechanism controlled by finger keys or a tape operated mechanism.

The collar N is mounted for limited rotation at the upper end of the vertically movable rod H and is formed with a groove n which (under the circumstances presently to be described) receives 10 the diametrically opposed pins N¹, N² projecting respectively from the levers E², F² that operate the line clamping jaws. When the collar is in its neutral position (as in Fig. 13), neither of the jaws will be operatively connected with the rod H for, although the pin N² associated with the right hand jaw projects beyond the edge of the collar N, the latter is cut out in its top portion as at n¹, to clear the pin, whereas the pin N¹ associated with the left hand jaw, and 20 which does not project quite so far beyond the face of its associated lever E² as does the pin N², normally stands free of the collar. Under these circumstances, the machine operates in the normal way, the line clamping jaws remaining fully 25 separated during casting.

The collar N is arranged to be rotated from its neutral position,—a quarter of a turn in a counterclockwise direction for quadding right, and a quarter of a turn in a clockwise direction 30 for centering.

When in the quadding right position (as in Fig. 14), the pin N² engages in the groove n of the collar to connect the right hand jaw through the lever F² with the vertically movable 35 rod H, the pin N¹ in this setting of the parts clearing the collar N as in the condition of normal operation. Under this setting, the right hand jaw F will be moved toward the left hand jaw under the influence of the rod H as the latter descends, to effect quadding at the right, and will be returned to its position of maximum separation as the rod is restored to normal position after casting operation.

When the collar N is rotated through a quarter of a turn in a clockwise direction for centering (as in Fig. 15), both the pin N² associated with the right hand jaw lever E² and the pin N¹ associated with the left hand jaw lever F² will engage in the groove n formed in the collar, so 40 that for this setting of the collar both the line clamping jaws will be connected to the vertically movable rod H, which therefore in descending will move the jaws equidistantly toward each other until arrested by contact with the opposite 45 ends of the line and later, in ascending, will restore the jaws to their original positions. It will be recalled that the pin N¹, in its normal position, does not extend as far beyond the face of its lever E² as does the pin N² beyond the face of 50 its lever F², but in the position of the collar N just referred to, proper cooperation between the parts is effected due to the fact that the collar N has a greater overhang in its edge portion adjacent the pin N¹ than in its remaining edge 55 portions.

For quadding left, the collar N remains in its neutral position (as in Fig. 16) and the pin N¹ (which in the normal position of the parts clears the collar N as the latter descends) is arranged 60 to be projected rearwardly into the groove n of the collar, the pin N¹ for this purpose being slidably mounted in the lever E² and formed with a reduced body portion presenting shoulders at the opposite ends which abut against the opposite 65

faces of said lever E², thus fixing the extent of travel of the pin in the fore-and-aft direction. The fore-and-aft movement of the pin N¹ is brought about through the operation of a U-shaped lever M (see Fig. 20) pivotally mounted near its center on a bracket M¹ screwed to the vise frame and arranged to be swung through a limited distance in a horizontal plane under the control of mechanism on the first elevator which 10 is set to operate the U-shaped lever automatically when the machine is conditioned for quadding left. This mechanism will be described in detail later. The U-shaped lever at its inner end is formed with an arcuate portion M² (see Fig. 2) 15 having a groove m in its outer edge adapted to receive a flanged head N³ formed at the outer end of the pin N¹. The arrangement of the parts is such that when the U-shaped lever is in its outermost position, the pin N¹ likewise will be 20 in its outermost or normal position, where it will clear the collar N; whereas, when the lever M is in its innermost position, the pin N¹ likewise will be in its innermost position where it will engage in the groove n formed in the collar N, 25 despite the fact the latter is still in its neutral position, as previously described. Under such conditions, the left hand line clamping jaw E will be connected through the collar N to the vertically movable rod H and, as the latter descends, the left hand jaw will be moved toward the right hand jaw until arrested by the composed line for quadding left. Furthermore, the connection between the U-shaped lever M and pin N¹ remains unbroken throughout the quadding operation, for, as the rod H descends to effect the inward movement of the jaw and then moves to its uppermost position to restore the parts to normal (carrying with it, as it does, the collar N), the head of the pin N¹ merely tracks 30 along in the groove m formed in the arcuate portion M² of the U-shaped lever (which remains in its innermost position), the shape of the arcuate portion conforming of course to the path the pin N¹ will follow as the lever E² turns upon its pivot. After the rod H reaches its uppermost 35 position, the lever M is swung outwardly to disengage the pin N¹ from the collar N.

At this point, it may be stated that the collar N is held in any of its adjusted positions by a spring 50 detent n² adapted to engage in any one of three depressions n³ formed in the rod H (see Fig. 12).

The collar N is turned from normal to one or another of its adjusted positions for quadding right and for centering) by one or another of a 55 pair of long rack bars O and O¹ arranged for limited up and down movement at the back of the first elevator C and in front of the vise frame D. The rack bars are guided in their up and down movement, at their upper ends, by a recessed plate O² screwed to the vise frame and, at their lower ends, in recesses formed in the first elevator at the rear thereof (see Figs. 2, 4, and 20). The rack bars adjacent their upper ends are equipped with teeth O³, O⁴ meshing at diametrically opposed points with a pinion O⁵ fixed to the front end of a hub O⁶ rotatably mounted on a stud O⁷ secured at its rear end in a bracket O⁸ on the vise frame and supported at its front end by the recessed plate O². The hub O⁶ is provided at its rear end with a second pinion O⁹ meshing at the bottom with a third pinion O¹⁰, which latter is fixed at the front end of a shaft O¹¹ rotatably mounted in the bracket O⁸ and provided at its rear end with a small bevelled gear O¹² adapted to mesh with a corresponding

bevelled gear N⁴ secured to the upper face of the collar N. The arrangement is such that as the right hand rack bar O is moved downwardly under the influence of the first elevator, as will be later described, the collar N, through the train of gears just mentioned, is rotated through a one-quarter turn in a counterclockwise direction to the position shown in Fig. 14, wherein the pin N² engages said collar to connect the vertically movable rod H with the right hand jaw for quadding right; whereas, when the left hand rack bar O¹ is moved downwardly to rotate the pinion O⁵, the collar N is turned a quarter of a turn in the opposite or clockwise direction, thus bringing it in the position shown in Fig. 15, wherein both 15 the pins N¹ and N² engage the collar to connect both line clamping jaws with the vertical movable rod H for centering.

It will likewise be noted that during this latter operation, that is, when the mechanism is conditioned for centering, the cam V¹ (which normally is in register with the roller h and which determines the extent of spread of the line clamping jaws during either of the quadding operations) is moved to the right and the cam V (which 20 controls the extent of jaw spread during centering) is brought into register with the roller h. This operation is brought about automatically by the movement of a slide O¹³ (Fig. 2) arranged for horizontal travel in the bracket O⁸ and, which, 25 upon being shifted to the left, operates, through a pin O¹⁴ carried thereby, a long lever V⁹ pivotally mounted at its center to the vise frame to shift the sleeve V² from the position shown in dotted lines in Fig. 2 (wherein the cam V¹ registers with the roll h) to the position shown in full lines wherein the other cam V registers with the roller. The connection of the lever V⁹ with the sleeve V² is through a long lower portion V¹⁰ of the lever which engages between a pair of flanges 30 V¹¹ formed on the sleeve, the length of the lower portion V¹⁰ of the lever being sufficient to accommodate the full travel of the sleeve as it is moved downwardly with the sleeve T during quadding or centering. Furthermore, when the 35 lever V⁹ moves to bring the cam V into action, such movement is against the tension of a spring V¹² anchored to the vise frame and which serves to restore the parts when the slide O¹³ is again returned to normal position. The normal position of the lever V⁹ and consequently the parts 40 affected thereby is determined by a pin O¹⁵ fixed in the bracket O⁸ adjacent the lower edge thereof and against which such lever at its upper end abuts.

The slide O⁸ is moved from normal position to the left as just described as the pinion O⁹ (which meshes with an overlying toothed rack bar O¹⁶ fixed to the slide) is rotated by the left hand rack bar O¹ in conditioning the grooved collar 50 N to effect the connection of the rod H with both line clamping jaws for centering, and is restored to normal position when the rack bar O¹ is moved upwardly after the casting operation.

The operation of the rack bars O, O¹ and the U-shaped lever M to effect the connection of the vertically movable rod H with the line clamping jaws E and F for the various conditions mentioned is brought about by mechanism carried by the first elevator and which is rendered operative immediately after the first elevator starts to descend from its line receiving position. This mechanism includes a pair of relatively short levers P and P¹ pivotally mounted adjacent their centers on the first elevator at a position some- 70 75

what below the center thereof and arranged to control one or another of the vertically movable rack bars O and O^1 , and a larger lever P^2 pivotally mounted at its center on a bracket P^5 fastened to the first elevator and which is designed to control the operation of the U-shaped lever M which functions in the setting of the devices for quadding left. Normally the levers P , P^1 , and P^2 are held under the control of a series of three trip dogs p , p^1 , and p^2 , one for each of said levers, pivotally mounted on a fore-and-aft rock shaft in a box P^3 screwed to the first elevator in a position just beneath the lower ends of the levers just referred to, said trip dogs being held in spaced relation by intermediate partitions p^3 .

The trip dogs (see Fig. 17) are formed with upstanding fingers p^5 which, in the normal position of the parts, stand in front of the levers P , P^1 , and P^2 at the lower ends thereof, the finger p^5 on the outer trip dog p^2 being arranged to cooperate with the long lever P^2 active in quadding left, that on the inner trip dog p^1 , with the short left hand lever P^1 active in centering, and that on the inner trip dog p with the short right hand lever P active in quadding right. The trip dogs are held in normal position by individual tension springs p^6 anchored to a rod p^7 extending transversely of the box P^3 at the upper left hand corner thereof.

The trip dogs are arranged to be selectively operated in the manner later to be described according as the machine is conditioned for a quadding right, a quadding left or a centering operation and, as the trip dogs are operated (immediately after the first elevator starts to descend), the lower portions of their respective levers P , P^1 , and P^2 will be allowed to swing forwardly to retain the trip dogs in their tripped position.

To be more specific, let it be assumed that it is desired to condition the machine for a centering operation which will involve the selection of the center trip dog p^1 for operation. As the first elevator starts to descend, said trip dog will be moved to a position (see Fig. 17) wherein the arresting finger p^5 thereon will free the short left hand lever P^1 and allow the lower end thereof to be drawn forwardly under the action of a tension spring p^8 secured to said lever and anchored at its front end to the wall member of the box P^3 until it banks against the partition p^3 immediately adjacent the front face of the trip dog p^1 (see Fig. 5), it being understood that the rear wall of the box P^3 and the partition at the rear of the trip dog p^1 are formed with notches to permit the passage of the lever P^1 . In this position of the lever P^1 , a shoe p^{10} (Fig. 5) screwed to the upper end thereof will overlie a shoulder c formed on the left hand rack bar O^1 and, as the first elevator continues in its descent, said rack bar will be drawn downwardly and through the train of gears between it and the grooved collar N , rotate the latter through a quarter of a turn to condition the machine for centering in the manner previously described. As the first elevator continues to descend, and after the downward movement of the rack bar O^1 has progressed sufficiently far to set the collar N , the lever P^1 is disengaged from the rack bar by the action

of a plate o^1 (Fig. 6) screwed to the vise frame in back of the first elevator and which is provided at its upper edge with a bevelled surface o^2 that reacts against a dog P^4 adjustably secured to the lever P^1 just above its pivot point to cam said lever back to normal position where it is

brought under the control of the trip dog p^1 as the latter springs back to normal position.

When the machine is set by the operator for quadding right, the inner trip dog p will be operated to free the right hand lever P which will operate in exactly the same way as the left hand lever to draw the right hand rack bar O downwardly to condition the parts for quadding right.

After the slug has been cast and the line clamping jaws restored to normal position by the upward movement of the rod H , the collar N is returned to normal position to effect the disconnection of the line clamping jaws, such action being brought about when the rack bar O or O^1 (whichever has been operated) is restored to normal position. The restoration of the rack bars is effected by the upward movement of the first elevator which, for this purpose is provided at its lower end with a bail member C^1 (Figs. 2 and 3) pivotally mounted on a pair of brackets c screwed to the first elevator. The bail member is formed with a pair of shoes c^1 , one for each of the rack bars, and in the normal position of the bail member, the rack bar O or O^1 (whichever happens to have been operated) is engaged by its respective shoe and is pushed upwardly into normal position as the elevator ascends. As the rack bar reaches its normal position, the ball member C^1 is rocked rearwardly against the tension of a spring c^2 anchored to the left hand bracket c to permit the elevator to ascend to its upper line transfer position, this rocking action being brought about by the engagement of an offset arm portion c^3 , formed at the left end of the bail member, with a banking stud d fixed to an arm d^1 depending from a bracket on the vise frame and positioned in the path of travel of said offset arm portion c^3 .

In the operation of the machine for quadding left, it will be recalled that the collar N remains in its neutral position and that the connection of the vertically movable rod H to the left hand jaw lever is effected by the fore-and-aft movement of the pin N^2 through the agency of the pivoted U-shaped lever M which in turn is operated by the long lever P^2 pivotally mounted on the first elevator. It will be recalled also that the lever P^2 is held in its normal position under the control of the outermost trip dog p^2 , the upstanding finger p^5 of which engages said lever at its lower end. When the operator sets the machine for quadding left, the outermost trip dog p^2 , as the first elevator starts to descend, will be turned to free the lever P^2 and the upper end thereof is immediately swung rearwardly under the influence of a pull spring p^{11} to actuate the U-shaped lever M , a shoe m^1 fixed at the extremity of the front arm of the lever M at this moment being directly behind and in the path of a corresponding shoe p^{12} secured to the upper end of the lever P^2 (see Fig. 10). A stop screw p^{13} protruding from the front face of the elevator limits the active stroke of the lever P^2 and thus saves undue wear and tear on the parts associated with the U-shaped lever M . The pin N^1 controlled by the lever M is thus projected into the groove n of the collar N and the machine is conditioned for quadding left. In the normal or inactive position of the lever P^2 (Fig. 4), as will be understood, the shoe p^{12} is adapted to pass the shoe m^1 without disturbing the U-shaped lever M during the vertical movements of the elevator C .

After the completion of the casting operation and the return of the left hand jaw to normal position through the upward movement of the

vertically movable rod H, the lever P² is restored to normal position during the ascent of the first elevator to its upper line transfer position. The devices for this purpose include (Fig. 11) a bevelled surface o³ formed at the lower edge of the rack retaining plate O² and which reacts against a roller p¹⁴ carried by the lever P² near its upper end to cam the lever back to normal position under the control of its associated trip dog p² as the latter springs back into normal position. Immediately after the lever P² has been restored to normal position, the U-shaped lever M is rotated in a clockwise direction to withdraw the pin N¹ out of the groove n in the collar N to disconnect the left hand jaw from the vertically movable rod H. This movement of the lever M is effected by the bracket P⁵, which supports the lever P² on the first elevator and which is formed at its outer end with a bevelled surface arranged to engage a complementary bevelled surface provided at the lower edge of the dog m¹ and cam the lever M to normal position as the first elevator continues to ascend (see Figs. 10 and 11).

The trip dogs p, p¹, p² are selectively operated according as the machine is conditioned for a quadding right, centering, or a quadding left operation by a set of three horizontal slides Q, (one for each trip dog) positioned at the right of the first elevator and just beneath the trip dogs when the first elevator is in its normal or line receiving position. The slides Q are arranged to be selectively projected into the path of fingers p⁴ formed on the corresponding trip dogs prior to the descent of the first elevator to casting position so that as the elevator starts to descend, the active slide will trip its corresponding trip dog and release the conditioning actuating mechanism controlled thereby. Immediately after the trip dog has been operated, the active slide is returned to normal position and it or either of the other slides may be set again immediately for controlling the conditioning of the next line even prior to the ascent of the first elevator to line transfer position for reasons and in the manner subsequently to be described.

The slides Q (Figs. 7 and 17) are arranged in a frame Q⁴ bracketed to the vise frame and which includes two side portions q, q¹, a pair of intermediate partitions q² for guiding the slides laterally, and a bottom portion q³ upon which the slides rest, but which is cut away at the left end to form a shoulder q⁴, against which downwardly projecting lugs q⁵ (one formed on each of the slides) abut when the slides are in their rightmost position, wherein they are normally held by tension springs Q⁶ secured to said lugs and anchored to studs q⁶ projecting from the bottom of the frame. The slides themselves are held in the frame by pin and slot connections q⁷ which in addition limit the movement of the slides toward the left. The slides are equipped each with a pivoted dog Q⁸ against which the trip dogs p, p¹ and p² react, the dogs Q⁸ being held against turning in one direction under the influence of the trip members by pins q⁸ projecting from the slides and against which the dogs rest in their normal positions. The dogs, however, are permitted to turn in the opposite direction against the tension of springs q⁹ connected to lugs formed on the lower portions of the dogs and anchored to the slides, this pivoting of the dogs being provided in the event that a slide Q set for one line has been restored and the same or another slide

set forth the next line while the elevator is still in its lower or line casting position.

As a further precaution against breakage of the parts, means are provided for permitting only one of the slides Q to be operated at a time. These safety means include (Figs. 17 and 18) a set of three pawls q¹⁰, q¹¹ and q¹² pivoted on pins q¹³ extending between the side walls of the frame Q⁴ and spring pressed to engage in combination notches q¹⁴ formed in the upper edges of the slides. The arrangement of the combination notches q¹⁴ is illustrated in Fig. 18. As shown, the pawl q¹⁰ at the left will cooperate with two short notches in the two innermost slides and one long notch in the outermost slide, the center pawl q¹¹ will cooperate with short notches in the outer and inner slides and a long notch in the center slide, while the third pawl q¹² (not shown in this view but shown in Fig. 17) will cooperate with two short notches in the two outer slides and a long notch in the inner slide. The relative positions of the notches are such that in the normal position of the parts, each pawl is immediately above two short notches but just to the left of the long notch in its associated combination where it rests against the upper edge of the slide having the long notch. Now it is evident that if any slide is actuated to the left, the long notch therein is brought in register with the pawl associated with that particular combination, whereupon said pawl will drop into all of the notches of such combination, thus effectively preventing the movement of the two slides formed with the short notches, but permitting the continued movement of the actuated slide through its proper distance because of the length of the long notch formed therein.

When the slides Q have been operated (it being understood that one only is operated at a time) they are retained in active position (Figs. 17 and 19) by latch dogs Q¹, one being provided for each slide, pivotally mounted at the upper left end of the slide housing Q⁴ and which are pulled down as the slides are moved to the left by tension springs q¹⁵ to a position wherein nose portions q¹⁶ formed at the ends of the dogs engage behind upstanding lugs q¹⁷ formed on the upper edges of said slides. Immediately after a trip member p, p¹ or p² (which selectively release the conditioning devices on the first elevator) has been operated and upon the continued descent of the first elevator, the latch dog Q¹ associated with the active slide is rocked by one of a set of three pawls p¹⁵, one for each latch dog, carried by the first elevator, and against the tension of its spring q¹⁵, to raise the nose portion q¹⁶ of the dog clear of the slide lug q¹⁷, thereby permitting the slide to be returned to normal position which it does under the influence of its spring Q⁶, the nose portion q¹⁶ coming to rest on the top of the lug q¹⁷ or in normal position. It will thus be seen that the slides Q are active for a brief period only, so that a slide may be set for conditioning the machine for a second line long prior to the time the casting of the first line has been completed.

The pawls p¹⁵ are pivotally mounted on a common shaft p¹⁶ extending between the front and rear walls of the bracket P³ (in which the trip members p, p¹ and p² are carried) and are held by torsion springs p¹⁷ against a stop p¹⁸, the arrangement being such that as the first elevator descends, not only will the dog Q¹ associated with the active slide be rocked, but also the other two in addition so as to permit the free passage of the pawls without interference, whereas upon the upward movement of the first elevator, said

pawls p^{15} will themselves be rocked against the tension of the springs p^{17} by the dogs Q^1 to permit passage of the pawls when the first elevator is moving upwardly. It might be here stated also that the nose portions of the dogs Q^6 on the slides Q are offset (see Fig. 19) so as not to interfere with the passage of the pawls p^{15} during the descent and ascent of the first elevator.

The slides Q are actuated to the left by a set of three levers S (Figs. 17 and 21) pivotally mounted adjacent their centers in a frame S^1 secured to the main frame of the machine. Each of the levers near its upper end is in register with one of the slides Q and is guided in its pivotal movement by partitions formed in the upper portion of the frame S^1 . The levers at their lower ends are formed with nose portions s^1 which in the normal position of the parts bank against nose portions s^2 formed at the ends of three corresponding lateral arms of a set of three ball members S^2 pivotally mounted on a shaft S^3 supported at its opposite ends in bearings carried by bracket means secured to the main frame (see also Figs. 1, 7, 8, and 9). Each of these ball members S^2 is selectively operated by one of three keys positioned adjacent the keyboard of the machine (one key for quadding left, one key for centering and one key for quadding right, as indicated by the letters L, C and R in Fig. 7) and, when a selected bail member S^2 is operated, the nose portion s^2 thereof is raised to permit the nose portion s^1 of the corresponding lever S to move beneath it into a bail notch s^3 provided for the purpose, such movement of the lever being effected by a spring S^4 connected thereto and anchored to a stud projecting from the lever supporting frame S^1 . However, the actuating lever S , which has been conditioned for operation by the bail member S^2 selected, does not actuate its associated slide Q immediately, for the levers are held against operation at this time by a pin s^4 provided at the lower end of a long offset lever S^5 . This lever S^5 is pivotally mounted adjacent its center on a bracket S^6 screwed to the main frame and is provided at its upper end with a roller s^5 riding in a cam groove a formed in a member A^1 screwed to the assembler A near its lower end (see Figs. 1, 8, and 9). The nose portion s^1 of the lever S selected for operation does, however (see Fig. 21) enter for a short distance beneath the nose s^2 of the corresponding ball member so that said lever will be in condition for operating the slide Q associated therewith when released by the pin s^4 , this action being due to the fact that certain clearance is provided between the pin s^4 and the slide actuating levers S .

When a line has been fully composed in the assembler A and the latter raised to a position just below the line transfer position (see Fig. 8) the roller s^5 will enter a depression a^2 formed in the same groove a , thus permitting the lever S^5 to turn in a clockwise direction, under the influence of a torsion spring s^6 arranged at its pivot point, to free the lever S that has been conditioned for operation by the ball member S^2 which previously was selectively operated from the keyboard. Immediately upon the release of a lever S , the slide Q corresponding thereto will be actuated to the left to position its associated dog Q^6 beneath the particular trip member p , p^1 or p^2 corresponding to the key selected.

As the assembler A continues to ascend to the line transfer position (see Fig. 9), the roller s^5 rides out of the depression a^2 , camming the lever S^5 in a counterclockwise direction to restore the

previously released slide operating lever S to normal position, it being understood that in doing this, the offset lever will have to pass slightly beyond its normal position in order to take care of the play or clearance before alluded to and which is normally present between the slide operating levers S and the pin s^4 . This operation is effected by a slightly raised surface a^3 immediately beneath the depression a^2 in the cam groove, and when the levers S have been fully restored, the bail member s^2 (whichever one has been actuated) will be permitted to return to its normal position to retain its associated lever S in place.

As previously stated, the bail members S^2 are controlled from a set of three finger keys (one for quadding left marked L, one for centering marked C, and one for quadding right marked R) and which are formed respectively at the ends of three horizontally arranged parallel key levers W pivotally mounted adjacent their centers in a frame W^1 screwed to the keyboard frame at the right (see Figs. 7, 22, and 23). The key levers W are connected to the bail members through a linkage arrangement including a set of three vertically movable rods W^2 mounted in a guide frame W^3 screwed to the keyboard supporting bracket and connected, at their upper ends each to one of the key levers through an offset plate W^4 notched at its end to receive a nose portion w formed at the end of each of said levers, and at their lower ends, each to one of a set of three rocker arms W^5 through a pin and slot connection w^1 . The rocker arms are pivotally mounted at their centers beneath the guide frame W^3 and are connected respectively to the bail members S^2 through links W^6 which are pivotally fastened at their upper ends to the rocker arms W^5 at the ends thereof opposite those at which the rods W^2 are connected, and at their lower ends to said bail members. The arrangement is such that as a key is depressed, its associated rod will be moved upwardly against the tension of a spring w^2 , one being provided for each rod, fastened to the rod and anchored to the guide frame W^1 to swing the associated rocker arm and depress the corresponding link W^6 which in turn rocks the bail member to release the proper slide controlling lever S . When the lever S which has been actuated is returned to normal position upon the full ascent of the assembler elevator in the manner previously described, the active bail member together with the corresponding key lever and intermediate linkage are restored to normal position by the tension springs w^2 referred to before.

It may of course be desired to maintain the setting of the machine for a given condition during the casting of a plurality of successive lines and for this purpose there are provided a set of locking levers W^7 , one for each key, pivotally mounted in the key lever frame just above the key levers and forward of the pivot points thereof. When the levers W^7 are in the position shown in solid lines in Fig. 22, such levers will be functionally inoperative, but when they are swung rearwardly to the position shown in dotted lines, the lower ends thereof will engage their respective key levers, thereby retaining the keys in a depressed condition, thus maintaining the nose of the bail member corresponding to the depressed key in a position always to release its associated slide operating lever S . It might be stated here, however, that the slide operating levers S do not remain in the set condition, for, it will be recalled that each time the line assembler is raised to the

line transfer position, these levers are restored to normal position by the lever S^5 , but under the conditions stated the lever S corresponding to the key locked down, will constantly maintain its engagement with the control pin s^4 so that when the assembler elevator is again lowered to the line assembly position, said slide operating lever will again enter slightly beneath the nose of its associated bail member, with the result that the same lever is in condition again to operate when the assembler is raised to transfer the next line.

Of course, it is quite essential that one key only be operated at a time; for, if more than one were operated, it would result in a condition where more than one of the slides Q would be actuated were it not for the presence of the locking pawls q^{11} which, under such circumstances, would prevent the actuation of any of the slides and thus give rise to the result that a short line would be presented to the mold under normal conditions of operation of the machine, and no casting operation would result. The operation of more than one key at a time is prevented by a pair of weighted dogs W^8 (Fig. 23a) pivotally mounted on a cross plate W^9 fastened to the key lever frame and beneath the key levers, the arrangement being such that if one key is operated, the dogs will assume a position beneath the other two keys, thus effectively preventing their operation. Thus, if the center key is operated, the dogs W^8 will be separated to assume a position one under the left hand key and the other under the right hand key, whereas, if the key at the left is operated, both dogs will be displaced to the right to assume a position, one under the center key and one under the right hand key; and should the right hand key be operated, the dogs will be actuated to the left, assuming a position, one under the center key and the other under the left hand key.

As stated at the outset, the machine may also be set automatically by mechanism operated from a perforated tape. The mechanism for this purpose is shown in Figs. 7 and 24 to 26, and may include a set of three solenoids W^{10} mounted on a bracket W^{24} secured to the machine frame and having their respective armatures W^{11} connected to a different one of the bail members through bell crank lever W^{12} pivotally mounted on the bail supporting shaft S^3 , so that by selectively energizing the solenoids to draw in their armatures, one or another of the bail members will be swung to release the corresponding slide actuating lever S in the same manner as this is done when the machine is operated by the finger keys.

The solenoids are connected in parallel to a source of electrical energy W^{13} through a set of three rectangular and pivotally mounted switches W^{14} which are provided at one end with bars W^{15} adapted to enter notches W^{16} formed in the usual code bars W^{17} .

In the normal position of the code bars (setting 1, Fig. 25), the bars W^{15} with which the switches are equipped will be held against the lower edges thereof by tension springs W^{18} , but when the code bars are set to bring a notch in each one thereof in register with one of the bars W^{15} , such bar will under the influence of its spring W^{18} , enter the row of aligned notches, with the result that the associated switch is caused to rock upon its pivot and close the circuit through the corresponding solenoid, thereby conditioning the machine for centering, quadding right, or quadding left, depending upon the setting of the code bars.

When the code bars are returned to normal posi-

tion, the circuit through the active solenoid is broken, permitting the associated bail member to be restored by the same mechanism provided for the purpose when the machine is operated with the finger keys, but after, of course, the corresponding slide operating lever S has been actuated and again restored to bail releasing position, which occurs as previously stated when the assembler is raised to line transfer position.

The code bars are six in number and are moved selectively to the left or right from normal position, depending upon the active combination of perforations in a tape W^{19} , such as is used with the teletypesetting machine for composing lines automatically. A typical tape is shown in Fig. 26, and is divided up horizontally into seven sections or rows, one for each of the code bars and a center section for feeding perforations to move the tape along. The tape is further divided up vertically into sections or rows, and each vertical row includes a combination of perforations, representing different matrices or spacebands which will be released from the magazines, or functions which the machine will perform. Thus in the example illustrated in Fig. 26, the first combination of perforations will, upon the setting of the code bars in accordance therewith, condition the machine for centering the line subsequently composed, which in this instance comprises the words "The Teletype" with a spaceband in between the words.

The setting of the code bars W^{17} in accordance with the tape combinations is effected by mechanism which includes a set of six pivotally mounted bell crank levers W^{20} , one for each code bar, provided each with a horizontal arm w^3 formed at its end with an upstanding pin w^4 adapted to enter perforations in the overriding tape, and with a depending vertical arm equipped at its lower end with two spaced legs w^5 and w^6 which serve as fulcrums for one of a set of underlying rocker arms W^{25} , likewise six in number, pivotally carried at their centers on a yoke W^{21} mounted on a rock shaft W^{22} , said rocker arms being formed each at its opposite ends with raised portions w^7 and w^8 corresponding respectively with the legs w^5 and w^6 although spaced somewhat further apart.

The arrangement is such that if no tape perforation registers with a pin w^4 of a bell crank lever W^{20} , such lever will assume a position wherein its leg w^6 will overlie the raised portion w^7 at one end of the corresponding rocker arm W^{25} ; whereas if a tape perforation does register with a pin w^4 of a bell crank lever, such lever will assume a position wherein its leg w^6 will overlie the raised portion w^8 at the opposite end of the rocker arm. The result is that as the yoke W^{21} is rocked in a counterclockwise direction, those rocker arms which fulcrum on the legs w^6 of the bell crank levers W^{20} (whose pins have entered perforations) will act to move the corresponding code bars to the left, whereas those rocker arms which fulcrum on the legs w^6 of the bell crank levers (whose pins have not entered perforations) will act to move the corresponding code bars to the right; the motion of the rocker arms being imparted to the code bars through arms w^9 depending from the rocker arms and engaging at their lower ends between lugs w^{10} formed in the upper edges of the code bars.

The rocking of the yoke in setting the code bars is effected by a cam w^{11} mounted on a rotatable shaft w^{12} and which imparts its action to the yoke through an arm w^{13} provided thereon and equipped with a cam follower spring pressed

against the edge of the cam. The form of the cam and the timing of its rotation is such that the rocker arms are not actuated until after the bell crank levers W^{20} have been set in accordance with 5 the perforation combination in the tape.

The bell crank levers W^{20} are rocked in one direction to cause the pins thereof to enter perforations in the tape by tension springs w^{14} , and in the opposite direction, to withdraw the pins 10 from the tape (to permit the latter to move along to the next combination) by a bail member W^{26} carried by a pivotally mounted U-shaped member W^{23} , and which engages beneath a set of arms w^{16} formed on the levers W^{20} . The movement of the 15 bail member is effected by a cam w^{17} mounted on the shaft w^{12} , through an intermediate arm depending from the U-shaped member and carrying at its lower end, a follower w^{18} spring pressed against the cam edge. The arrangement is such 20 that after the code bars have been restored to normal position in the usual way, a high portion of the cam w^{17} will engage the follower w^{18} to raise the bail and withdraw those levers W^{20} which have entered the perforations so that the 25 tape can be advanced to the next position. The movement of the levers W^{20} in either direction from normal is limited by a rod w^{19} which passes through an oversized hole formed in each of said levers.

30 It can now be seen how the perforation combinations for centering, quadding left and quadding right will effect the operation of the switches W^{14} which, through the solenoids W^{10} , set the bail members S^2 . In Fig. 25 the code bars and tape 35 are shown inverted, so that the position of the notches W^{16} in the different settings of the code bars may be observed. The code bars in their normal position are shown in setting #1 and the relative positions of the bars W^{15} on the rocker 40 switches indicated in dotted lines. The perforation combination for quadding left includes five perforations, one in each horizontal row with the exception of row 3. Accordingly, as previously described, the code bars for which perforations 45 have been provided, will be actuated to the left, whereas that for which no perforation has been provided will be actuated to the right. In this setting of the code bars, one notch in each bar will be brought into register with the bar W^{15} of 50 the switch that controls the conditioning of the machine for quadding left. And likewise the perforation combinations for centering and quadding right (see settings #3 and #4) are such that the code bars will be brought into positions 55 wherein a notch in each code bar will register with the bar W^{15} of the switches W^{14} controlling the conditioning of the machine for centering and quadding right respectively. In this way the conditioning of the machine for the various 60 functions referred to will be entirely automatic.

It is believed the foregoing description will suffice for a perfect understanding of the invention without going further into the details of operation of the machine. It might be stated 65 here however, that one of the principal advantages flowing from the use of the invention is the speed with which the composed lines may be sent through the machine. Heretofore, it was necessary for the operator to watch the casting 70 mechanism in order to make the desired adjustments of the quadding and centering devices as quickly as possible after the casting operation, and then shift his attention back to the keyboard to continue his work of line assemblage 75 or composition.

With the instant invention, however, the machine may be adjusted for quadding or centering and the lines cast at the same rate as when operating normally, due to the fact that the bail members S^2 may be set for any condition, irrespective of the previous setting of the slide members Q , and since the latter are restored to normal position during the descent of the first elevator to the casting level, they may be immediately reset as the assembler with the next 10 composed line is raised to line transfer level. In this way, it is possible to have a waiting line in the intermediate channel while the previous line is still in the first elevator, and there can be absolutely no delay in the operation of the machine. Furthermore, the parts (other than those operated by periodically moving parts of the machine) may be set either before or after the line has been composed or indeed at any time 15 during the composition of the line in the assembler. These advantages are present whether the conditioning means be controlled by finger keys or by a perforated tape. However, when controlled by a perforated tape, there is the further advantage which comes from wholly automatic control, it being possible for the first 20 time to equip a tape operated machine (such as the teletypesetter) with a quadding and centering device. These and other advantages 25 will be readily appreciated by those skilled in the art.

In the accompanying drawings, the invention has been shown merely by way of example and in preferred form, and obviously many variations and modifications may be made therein which 30 will still be comprised within its spirit. It is to be understood, therefore, that the invention is not limited to any specific form or embodiment, except insofar as such limitations are 35 specified in the appended claims.

Having thus described my invention, what I 40 claim is:

1. In a slug casting machine, the combination of a pair of line clamping jaws, one movable toward the other for quadding, mechanism to 45 effect such quadding movement of the jaw, means to condition said mechanism for a quadding operation, and means independent of the composed line to actuate the conditioning mechanism automatically during a given casting cycle 50 when a quadding operation is to be performed.

2. In a slug casting machine, the combination of a pair of line clamping jaws, one movable toward the other for quadding, mechanism to 55 effect such quadding movement of the jaw, means to condition said mechanism for a quadding operation, means to actuate the conditioning mechanism automatically when a quadding operation is to be performed, and means independent of the composed line to render said actuating means active or inactive for a given casting cycle as 60 required.

3. In a slug casting machine, the combination of a pair of line clamping jaws, one movable toward the other for quadding, mechanism to 65 effect such quadding movement of the jaw, means to condition said mechanism for a quadding operation, means to actuate the conditioning mechanism automatically when a quadding operation is to be performed, said actuating means being normally inactive, and manually controlled means to render the actuating means active for 70 a given casting cycle when required.

4. In a slug casting machine, the combination of a pair of line clamping jaws, one movable 75

toward the other for quadding, mechanism to effect such quadding movement of the jaw, means to condition said mechanism for a quadding operation, means to actuate the conditioning mechanism automatically when a quadding operation is to be performed, said actuating means being normally inactive, and automatically controlled means independent of the length of the composed line to render the actuating means active 10 for a given casting cycle when required.

5. In a slug casting machine, the combination of a pair of line clamping jaws, each movable independently toward the other for quadding right or quadding left, mechanism to effect such quadding movement of the jaws, means to condition said mechanism for a quadding operation with either jaw, and means to actuate the conditioning mechanism automatically and in accordance with the jaw selected for quadding.

20 6. In a slug casting machine, the combination of a pair of line clamping jaws, each movable independently toward the other for quadding right or quadding left, mechanism to effect such quadding movement of the jaws, means to condition said mechanism for a quadding operation with either jaw, means to actuate the conditioning mechanism automatically, and manually controlled means to govern the operation of the actuating means for a given casting cycle in accordance with the jaw selected for quadding.

35 7. In a slug casting machine, the combination of a pair of line clamping jaws, each movable independently toward the other for quadding right or quadding left, mechanism to effect such quadding movement of the jaws, means to condition said mechanism for a quadding operation with either jaw, means to actuate the conditioning mechanism automatically, and automatically controlled means to govern the operation of the actuating means for a given casting cycle in accordance with the jaw selected for quadding.

40 8. In a slug casting machine, the combination of a pair of line clamping jaws movable one relatively to the other for quadding or equidistantly toward each other for centering, mechanism to effect such quadding or centering movement of the jaws, means to condition said mechanism for a quadding or centering operation, and means to actuate the conditioning mechanism automatically and according as a quadding or centering operation is to be performed.

45 9. In a slug casting machine, the combination of a pair of line clamping jaws movable one relatively to the other for quadding or equidistantly toward each other for centering, mechanism to effect such quadding or centering movement of the jaws, means to condition said mechanism for a quadding or centering operation, means to actuate the conditioning mechanism automatically, and manually controlled means to govern the operation of said actuating means for a given casting cycle according as a quadding or centering operation is to be performed.

60 10. In a slug casting machine, the combination of a pair of line clamping jaws movable one relatively to the other for quadding or equidistantly toward each other for centering, mechanism to effect such quadding or centering movement of the jaws, means to condition said mechanism for a quadding or centering operation, means to actuate the conditioning mechanism automatically, and automatically controlled means to govern the operation of said actuating means for a given casting cycle according as a

quadding or centering operation is to be performed.

11. In a slug casting machine, the combination of a pair of line clamping jaws, each movable independently toward the other for quadding right or quadding left, and both movable in unison equi-distantly toward each other for centering, mechanism to effect such quadding or centering movement of the jaws, means to condition said mechanism for quadding right, quadding left, or for centering, and means operable during a casting cycle to actuate the conditioning means automatically and in accordance with the quadding or centering operation to be performed.

15 12. In a slug casting machine, the combination of a pair of line clamping jaws, each movable independently toward the other for quadding right or quadding left, and both movable in unison equi-distantly toward each other for centering, mechanism to effect such quadding or centering movement of the jaws, means to condition said mechanism for quadding right, quadding left, or for centering, means operable during a casting cycle to actuate the conditioning means automatically, and manually controlled means to govern the operation of said actuating means for a given casting cycle according as the jaws are selected for quadding right, quadding left, or for centering.

20 13. In a slug casting machine, the combination of a pair of line clamping jaws, each movable independently toward the other for quadding right or quadding left, and both movable in unison equi-distantly toward each other for centering, mechanism to effect such quadding or centering movement of the jaws, means to condition said mechanism for quadding right, quadding left, or for centering, means operable during a casting cycle to actuate the conditioning means automatically, and automatically controlled means to govern the operation of said actuating means for a given casting cycle according as the jaws are selected for quadding right, quadding left, or for centering.

25 14. A combination according to claim 3, including automatic means for restoring the actuating means to its original condition upon completion of the casting cycle.

30 15. In a slug casting machine equipped with a vertically movable line transporter, the combination of a pair of line clamping jaws, an operating device therefor, and means independent of the composed line actuated by the downward movement of the transporter for connecting one of said jaws to the operating device for quadding.

35 16. In a slug casting machine equipped with a vertically movable line transporter, the combination of a pair of line clamping jaws, an operating device therefor, and means independent of the composed line actuated by the downward movement of the transporter for connecting one of said jaws to the operating device for quadding, said means being actuated by the upward movement of the transporter for disconnecting said 40 jaw from the operating device.

45 17. In a slug casting machine equipped with a vertically movable line transporter, the combination of a pair of line clamping jaws, an operating device therefor, and means actuated by the downward movement of the transporter for connecting either of said jaws to the operating device for quadding right or quadding left as required.

50 18. In a slug casting machine equipped with a

- vertically movable line transporter, the combination of a pair of line clamping jaws, an operating device therefor, and means actuated by the downward movement of the transporter for connecting either of said jaws to the operating device for quadding right or quadding left as required, said means being actuated by the upward movement of the transporter for disconnecting said jaw from the operating device.
19. In a slug casting machine equipped with a vertically movable line transporter, the combination of a pair of line clamping jaws, an operating device therefor, and means actuated by the downward movement of the transporter for connecting one or both of said jaws to the operating device for quadding or centering as required.
20. In a slug casting machine equipped with a vertically movable line transporter, the combination of a pair of line clamping jaws, an operating device therefor, and means actuated by the downward movement of the transporter for connecting one or both of said jaws to the operating device for quadding or centering as required, said means being actuated by the upward movement of the transporter for disconnecting the jaw or jaws from the operating device.
21. A combination according to claim 15, including means for rendering the transporter actuated means active or inactive as required.
22. In a slug casting machine equipped with a vertically movable line transporter, the combination of a pair of line clamping jaws, an operating device therefor, means for connecting one of the jaws to the operating device, a member carried by the transporter for actuating the connecting means in the downward movement of the transporter for quadding, a trip dog also carried by the transporter for holding said member normally in inactive position, and means for operating the trip dog to render said actuating member active when required.
23. In a slug casting machine equipped with a vertically movable line transporter, the combination of a pair of line clamping jaws, an operating device therefor, means for connecting one of the jaws to the operating device, a member carried by the transporter for actuating the connecting means in the downward movement of the transporter for quadding, a trip dog also carried by the transporter for holding said member normally in inactive position, means for operating the trip dog to render said actuating member active when required, and means acting upon the upward movement of the transporter for restoring said actuating member to inactive position under the control of its trip dog.
24. In a slug casting machine equipped with a vertically movable line transporter, the combination of a pair of line clamping jaws, an operating device therefor, means for connecting one or both of the jaws to the operating device, a plurality of members carried by the transporter for actuating the connecting means in the downward movement of the transporter for quadding or centering as required, a corresponding plurality of trip dogs also carried by the transporter for holding said actuating members normally in inactive position, and means for operating one of the trip dogs at a time to render the corresponding actuating member active when required.
25. In a slug casting machine equipped with a vertically movable line transporter, the combination of a pair of line clamping jaws, an operating device therefor, means for connecting one or both of the jaws to the operating device, a plurality of members carried by the transporter for actuating the connecting means in the downward movement of the transporter for quadding or centering as required, a corresponding plurality of trip dogs also carried by the transporter for holding said actuating members normally in inactive position, and means for operating one of the trip dogs at a time to render the corresponding actuating member active when required.
- members carried by the transporter for actuating the connecting means in the downward movement of the transporter for quadding or centering as required, a corresponding plurality of trip dogs also carried by the transporter for holding said actuating members normally in inactive position, means for operating one of the trip dogs at a time to render the corresponding actuating member active when required, and means acting upon the upward movement of the transporter for restoring said actuating member to inactive position under the control of its trip dog.
26. In a slug casting machine equipped with a vertically movable line transporter, the combination of a pair of line clamping jaws, an operating device therefor, means for connecting one of the jaws to the operating device for quadding, a member carried by the transporter for actuating the connecting means in the downward movement of the transporter, a trip dog also carried by the transporter for holding said actuating member in inactive position, and a slide mounted independently of the transporter and settable in position to engage and operate the trip dog to render the actuating member active when required.
27. In a slug casting machine equipped with a vertically movable line transporter, the combination of a pair of line clamping jaws, an operating device therefor, means for connecting one of the jaws to the operating device for quadding, a member carried by the transporter for actuating the connecting means in the downward movement of the transporter, a trip dog also carried by the transporter for holding said actuating member in inactive position, a slide mounted independently of the transporter and settable in position to engage and operate the trip dog to render the actuating member active when required, and means controlled by the downward movement of the transporter for restoring the set slide to its original position after it has operated the trip dog.
28. In a slug casting machine equipped with a vertically movable line transporter, the combination of a pair of line clamping jaws, an operating device therefor, means for connecting one of the jaws to the operating device for quadding, a member carried by the transporter for actuating the connecting means in the downward movement of the transporter, a trip dog also carried by the transporter for holding said actuating member in inactive position, a slide mounted independently of the transporter and settable in position to engage and operate the trip dog to render the actuating member active when required, means controlled by the downward movement of the transporter for restoring the set slide to its original position after it has operated the trip dog, and means actuated by the upward movement of the transporter for restoring the actuating member to inactive position under the control of its trip dog.
29. In a slug casting machine equipped with a vertically movable line transporter, the combination of a pair of line clamping jaws, an operating device therefor, means for connecting one or both of said jaws to the operating device for quadding or centering as required, a plurality of members carried by the transporter for actuating the connecting means in the downward movement of the transporter, a corresponding plurality of trip dogs also carried by the transporter for holding said members normally in inactive position, and a corresponding plurality of slides mounted independently of the transporter and settable in position to engage and operate the trip dogs to render the actuating members active when required.

- one settable at a time in position to engage and operate its trip dog to render the corresponding actuating member active for quadding or centering as the case may be.
5. 30. In a slug casting machine equipped with a vertically movable line transporter, the combination of a pair of line clamping jaws, an operating device therefor, means for connecting one or both of said jaws to the operating device for quadding or centering as required, a plurality of members carried by the transporter for actuating the connecting means in the downward movement of the transporter, a corresponding plurality of trip dogs also carried by the transporter for holding 10 said members normally in inactive position, a corresponding plurality of slides mounted independently of the transporter and one settable at a time in position to engage and operate its trip dog to render the corresponding actuating member active for quadding or centering as the case may be, and means controlled by the downward movement of the transporter for restoring the set slide to its original position after it has operated its trip dog.
15. 31. In a slug casting machine equipped with a vertically movable line transporter, the combination of a pair of line clamping jaws, an operating device therefor, means for connecting one or both of said jaws to the operating device for quadding or centering as required, a plurality of members carried by the transporter for actuating the connecting means in the downward movement of the transporter, a corresponding plurality of trip dogs also carried by the transporter for holding 20 said members normally in inactive position, a corresponding plurality of slides mounted independently of the transporter and one settable at a time in position to engage and operate its trip dog to render the corresponding actuating member active for quadding or centering as the case may be, and means controlled by the downward movement of the transporter for restoring the set slide to its original position after it has operated its trip dog.
25. 32. A combination according to claim 29, including selective means for setting one or another of the slides in engaging relation to its trip dog for quadding or centering as the case may be.
30. 33. A combination according to claim 29, including a plurality of finger keys, one for each slide, for setting one or another of the slides in engaging relation to its trip dog for quadding or centering as the case may be.
35. 34. A combination according to claim 29, including tape-operated means for setting one or another of the slides in engaging relation to its trip dog for quadding or centering as the case may be.
40. 35. A combination according to claim 29, including selective means for setting one or another of the slides in engaging relation to its trip dog for quadding or centering as the case may be, and means for delaying the setting of the slides until the composed line for which the setting is intended has been started on its way to the transporter.
45. 36. A combination according to claim 29, including selective means for setting one or another of the slides in engaging relation to its trip dog for quadding or centering as the case may be, and means for preventing more than one slide at 50 a time from being set in engaging relation to its trip dog.
5. 37. A combination according to claim 29, including a plurality of finger keys, one for each slide, for setting one or another of the slides in engaging relation to its trip dog for quadding or centering as the case may be, and means for preventing the operation of more than one finger key at a time.
10. 38. In a slug casting machine, the combination of a pair of line clamping jaws movable one relatively to the other for quadding or equi-distantly toward each other for centering, mechanism to effect such movement of the jaws, and automatic means to condition said mechanism for a quadding or centering operation as required.
15. 39. In a slug casting machine, the combination of a pair of line clamping jaws movable one relatively to the other for quadding or equi-distantly toward each other for centering, mechanism to effect such movement of the jaws, and tape-operated means to condition said mechanism for a quadding or centering operation as required.
20. 40. In a slug casting machine, the combination of a pair of line clamping jaws, one movable relatively toward the other for quadding, mechanism to effect such quadding movement of the jaw, and tape-operated means to condition said mechanism for a quadding operation when required.
25. 41. In a slug casting machine, the combination of a pair of line clamping jaws, an operating device therefor, and tape-operated means for connecting one of said jaws to the operating device for quadding.
30. 42. In a slug casting machine, the combination of a pair of line clamping jaws, an operating device therefor, and tape-operated means for connecting one or both of said jaws to the operating device for quadding or centering as required.
35. 43. In a slug casting machine, the combination of a pair of line clamping jaws, one movable toward the other for quadding, mechanism to effect such quadding movement of the jaw, means to condition said mechanism for a quadding operation, means to actuate the conditioning mechanism automatically when a quadding operation is to be performed, settable devices for rendering the actuating means active during a given casting cycle, and means for actuating the settable devices as the line, after composition, is forwarded for casting.
40. 44. In a slug casting machine, the combination of a pair of line clamping jaws, each movable toward the other for quadding right or quadding left, mechanism to effect such quadding movement of the jaws, means to condition said mechanism for a quadding operation with either jaw, means to actuate the conditioning mechanism automatically, a plurality of devices selectively settable according as a quadding operation with either jaw is to be performed for rendering the actuating means active, and means for moving the device selected to its set position as the line after composition is forwarded for casting.
45. 45. In a slug casting machine, the combination of a pair of line clamping jaws, one movable relatively to the other for quadding or equi-distantly toward each other for centering, mechanism to effect such quadding or centering movement of the jaws, means to condition said mechanism for a quadding or a centering operation, means to actuate the conditioning mechanism automatically, a plurality of devices selectively settable according as a quadding or centering operation is to be performed for rendering the ac- 50

tuating means active, and means for moving the device selected to its set position as the line after composition is forwarded for casting.

46. In a slug casting machine, the combination of a pair of line clamping jaws, each movable independently toward the other for quadding right or quadding left, and both movable in unison equi-distantly toward each other for centering, mechanism to effect such quadding or centering movement of the jaws, means to condition said mechanism for quadding right, quadding left, or for centering, means operable during a casting cycle to actuate the conditioning means automatically, a plurality of devices selectively settable according as a quadding operation with either jaw or a centering operation with both jaws is to be performed for rendering the actuating means active, and means for moving the device selected to its set position as the line after composition is forwarded for casting.

47. A combination according to claim 43, wherein the settable devices are conditioned for movement to the set position prior to the forwarding of the composed line.

48. A combination according to claim 43, wherein the settable devices are conditioned manually for movement to the set position.

49. A combination according to claim 43, wherein the settable devices are conditioned automatically by tape-operated mechanism for movement to the set position.

50. A combination according to claim 43, wherein the means for moving the settable devices is controlled by the line forwarding movement of the assembler elevator.

51. A combination according to claim 4, including automatic means for, restoring the actuating means to its original condition upon completion of the casting cycle.

52. A combination according to claim 16, including means for rendering the transporter actuated means active or inactive as required.

53. In a linecasting machine, a casting mechanism including means for holding assembled lines of matrices comprising a pair of jaws slidable for embracing said matrices, and a signal controlled apparatus including power initiating means for selectively moving said jaws individually or concurrently.

54. In a linecasting and composing machine, a matrix composing mechanism, a casting mechanism, means for moving assembled lines of matrices from a point of assembly in said composing mechanism to said casting mechanism, and an automatic control unit responsive to storage signals including a plurality of individually selectable elements allotted to the selective control of said casting mechanism.

55. In a linecasting and composing machine, a composing mechanism, a casting mechanism, means for supporting a line of matrices during its transit from said composing mechanism to said casting mechanism, and means for concurrently storing a casting mechanism control signal associated with said line in said supporting means.

56. In a linecasting mechanism, a mold within which line composition slugs are cast, a carriage for supporting an assembled line of matrices opposite to and in cooperation with said mold including a matrix clamping jaw for confining said assembled matrices, and means under the control of stored signals for selectively actuating said jaw.

57. In a linecasting machine, a slug casting

mold, an apparatus for holding assembled lines of matrices in casting position, a pair of vise jaws cooperating with said apparatus for clamping assembled lines of matrices during casting operation, and signal controlled mechanism for actuating either or both said vise jaws under the control of predetermined storage signals.

58. In a mechanism of automatic line composition, slug casting apparatus including quad control vises capable of a plurality of conditions of operation, an element movable into selective positions corresponding to said conditions of operation, a record reader mechanism responsive to the perforations in a tape, including a plurality of selectable elements each corresponding to one of said conditions of operation, and means under the control of each of said elements for moving said control element into a corresponding one of its alternative positions.

59. In a slug casting machine, the combination of a pair of line clamping jaws, one movable toward the other for quadding, mechanism to effect such quadding movement of the jaw, and means controlled by a stored signal to condition said mechanism for a quadding operation.

60. In a slug casting machine, the combination of a pair of line clamping jaws movable one relatively to the other for quadding or equidistantly toward each other for centering, mechanism to effect such movement of the jaws, and means controlled by a stored signal to condition said mechanism for a quadding or centering operation as required.

61. In a slug casting machine, the combination of a pair of line clamping jaws, one movable toward the other for quadding, mechanism to effect such quadding movement of the jaw, said mechanism being normally inactive, means controlled by a stored signal to condition said mechanism for a quadding operation, and automatic means to render said mechanism inactive after each quadding operation.

62. In a slug casting machine, the combination of a pair of line clamping jaws movable one relatively to the other for quadding or equidistantly toward each other for centering, mechanism to effect such movement of the jaws, said mechanism being normally inactive, means controlled by a stored signal to condition said mechanism for a quadding or centering operation as required, and automatic means to render said mechanism inactive after each quadding or centering operation.

63. In a slug casting machine, the combination of a pair of line clamping jaws, one movable toward the other for quadding, mechanism to effect such quadding movement of the jaw, means to condition said mechanism for a quadding operation, and signal storing means to control said conditioning mechanism for the performance of quadding operations during predetermined casting cycles.

64. In a slug casting machine, the combination of a pair of line clamping jaws movable one relatively to the other for quadding or equidistantly toward each other for centering, mechanism to effect such movement of the jaws, means to condition said mechanism for a quadding or centering operation as required, and signal storing means to control said conditioning mechanism for the performance of quadding or centering operations during predetermined casting cycles.

65. In a slug casting machine, the combination of a pair of line clamping jaws, one movable toward the other for quadding, mechanism to ef-

fect such quadding movement of the jaw, mechanical means to condition said mechanism for a quadding operation, and signal storing means to control said conditioning means.

5 66. In a slug casting machine, the combination of a pair of line clamping jaws, one movable toward the other for quadding, mechanism to effect such quadding movement of the jaw, mechanical means to condition said mechanism for a quadding operation, and mechanical signal storing means to control said conditioning means.

10 67. In a slug casting machine, the combination of a pair of line clamping jaws, one movable toward the other for quadding, mechanism to effect such quadding movement of the jaw, mechanical means to condition said mechanism for a quadding operation, and mechanical signal storing means to control said conditioning means, said signal storing means being responsive to the actuation of manually operated finger keys.

15 68. In a slug casting machine, the combination of a pair of line clamping jaws, one movable toward the other for quadding, mechanism to effect such quadding movement of the jaw, mechanical means to condition said mechanism for a quadding operation, and mechanical signal storing means to control said conditioning means, said signal storing means being responsive to the actuation of electro-magnets under the control of 20 a perforated tape.

69. In a slug casting machine, the combination of a pair of line clamping jaws movable one relatively to the other for quadding or equidistantly toward each other for centering, an operating device normally disconnected from the jaws, automatic means for connecting one or both of said jaws to the operating device for a quadding or centering operation as required, and automatic means for disconnecting the operating device from the jaw or jaws after each quadding or centering operation. 5

70. In a slug casting machine, the combination of a pair of line clamping jaws, one movable toward the other for quadding, mechanism to effect such quadding movement of the jaw, means to 15 condition said mechanism for a quadding operation, and automatic means to actuate said conditioning mechanism during given casting cycles according to a prearranged sequence.

71. In a slug casting machine, the combination of a pair of line clamping jaws movable one relatively to the other for quadding or equidistantly toward each other for centering, mechanism to effect such movement of the jaws, means to condition said mechanism for a quadding or centering 25 operation as required, and automatic means to actuate said conditioning mechanism during given casting cycles according to a prearranged sequence. 20

FRANK C. FROLANDER. 30
